LOUD-SPEAKER HOUSING OR SIMILAR ARTICLE

Allison A. Turner, 90 Grays Road North, Stoney Creek,
Ontario, Canada

Filed Sept. 25, 1964, Ser. No. 81,868

Term of patent 14 years

(Cl. D26—14)

FIG. 1

FIG. 2

FIG. 3

FIG. 4

FIG. 5

FIG. 6

FIG. 7

FIG. 8

FIGURE 1 is a front elevational view of a loud-speaker housing or similar article, showing one form of my new design;

FIGURE 2 is a side elevational view of the form shown in FIGURE 1, the opposite side being substantially a mirror image thereof;

FIGURE 3 is a top plan view of the form shown in FIGURE 1;

FIGURE 4 is a bottom plan view of the form shown in FIGURE 1;

FIGURE 5 is a front elevational view of a loud-speaker housing or similar article, showing another form of my new design;

FIGURE 6 is a side elevational view of the form shown in FIGURE 5, the opposite side being substantially a mirror image thereof;

FIGURE 7 is a top plan view of the form shown in FIGURE 5; and

FIGURE 8 is a bottom plan view of the form shown in FIGURE 5.

The broken line showing a loud-speaker in FIGURES 3 and 7 is for illustrative purposes only.

I claim:

The ornamental design for a loud-speaker housing or similar article, substantially as shown and described.
